ROTARY KILN

Charles S. Lincoln and Arthur J. Jorgensen,
Wauwatosa, Wis., assignors to Allis-Chalmers
Manufacturing Company, Milwaukee, Wis., a
corporation of Delaware

Application May 31, 1941, Serial No. 396,038

16 Claims. (Cl. 263—32)

This invention relates generally to kilns and the like and more particularly to an end section construction therefor.

A kiln end section construction heretofore commonly employed comprises a metal wedge ring presenting an outer cylindrical surface adapted to engage the inner surface of a cylindrical kiln shell and the wedge ring, which is usually formed with solid metal segments, is disposed partially within the discharge end of the kiln shell and is secured thereto by means of radially extending bolts, rivets or the like. The inner surface is covered with a refractory lining adapted to form a continuation of the lining within said shell and the expansion of the refractory lining frequently shears the retaining bolts or rivets and forces one or more of the ring segments out the end of the kiln shell. Another kiln end section construction which also has heretofore been commonly employed comprises in effect an angle shaped metal end ring having its inner surface protected by a refractory lining a part of which lies partially within the angle. However, the outer end flange of this ring is not entirely protected by the refractory lining and consequently, the outer end flange is rapidly burned away by the high temperature material leaving the kiln, and the ring, which becomes highly heated, warps and allows the refractory lining, which is then loose, to fall out the adjacent end of the kiln. Moreover, the metal ring, which is usually made in segments is in many instances removably secured to the metal shell of the kiln by means of bolts or the like which pass through aligned openings provided in the inner flange of the ring and in the abutting or coating flange formed on or secured to the adjacent end of the shell and as a result, the expansion of the refractory lining may shear the ring retaining bolts and allow one or more of the ring segments to fall out of the kiln.

It is therefore an object of this invention to provide an improved end section construction for kilns in which no part of the refractory retaining metal end ring is exposed directly to the high temperature material leaving the kiln.

Another object of this invention is to provide an improved end section construction for kilns in that the refractory retaining metal end segments are secured to the metal shell of the kiln in a manner which materially reduces warpage and the shearing stresses imparted to the retaining bolts and the like.

Still another object of this invention is to provide an improved end section construction for kilns in that the refractory retaining metal end

ring segments are disposed concentrically within the metal shell of the kiln and are secured thereto in a manner subjecting the metal end ring segments and the securing means therefor to the action of a cooling fluid.

A further object of this invention is to provide an improved end section construction for kilns which is extremely durable and relatively inexpensive and which can be readily installed and 10 replaced if necessary with a minimum of effort.

The invention accordingly consists of the various features of construction, combinations of elements and arrangements of parts as more particularly set forth in the appended claims and 15 in the detailed description, in which:

Fig. 1 is a sectional view of a kiln end section construction embodying the invention;

Fig. 2 is an enlarged sectional view of the end section construction taken on line II—II of Fig. 6;

20 Fig. 3 is an end view of a retaining end ring segment;

Fig. 4 is a bottom view of the retaining end ring segment shown in Fig. 3;

Fig. 5 is a partial sectional view taken on line 25 V—V of Fig. 2;

Fig. 6 is a partial sectional view taken on line VI—VI of Fig. 2; and

Fig. 7 is a partial sectional view taken on line 30 VII—VII of Fig. 2.

Referring to the drawing and particularly Figs. 1 and 2, it is seen that the kiln end section construction comprises a rubbing ring 1, an end ring 2, and a shell ring 3. The rubbing ring 1 has its inner surface provided with a series of axially extending and circumferentially spaced ribs 4 adapted to engage the outer surface of the kiln shell 6 and define therewith air passages 5 (see Fig. 5) which place the space provided between the inner surface of the shell ring 3 and the op-

35 posed outer surfaces of the end ring 2 and the kiln shell 6 in communication with the atmosphere. The end portion of the shell 6 is provided with three axially spaced and circumferentially extending series of openings 7, 8 and 9, and 40 the rubbing ring 1 is provided with two axially spaced and circumferentially extending series of openings 11 and 12 arranged for alignment with the series of openings 7 and 8 in the shell 6. The openings 11 and 12 extend through the ribs 4 as is best shown in Figs. 1, 2 and 5. The rubbing ring 1 is first placed on the shell 6 with the series of openings 11 and 12 aligned with the series of openings 7 and 8, and the ring 1 is initially se-

45 cured in this position by means of the rivets 13

or the like which extend through the alined series of openings 7 and 11.

The end ring 2 is formed by a plurality of similar segments 14 each having cylinder and cone frustum forming portions 16 and 17, respectively. The outer surface of each segment 14 is provided with two pairs of axially spaced bosses 18 and 19, respectively. The bosses 18 and 19 each have an opening 21 and 22, respectively, which extend therethrough in a radial direction and the arrangement of the bosses 18 and 19 is such that the openings 21 and 22 can be alined with the series of openings 8 and 9, respectively, in the kiln shell 6. The bosses 19 are dimensioned to extend within the series of openings 8 in the shell 6 to thereby aid in correctly positioning and retaining the segments 14 within the discharge end of the kiln shell 6. The openings 21 and 22 each terminate in an enlarged bolt head receiving recess 23 and 24, respectively, formed in the inner surface of the segment 14 as is clearly indicated in Figs. 1, 2, 4, 5 and 6. The outer end portion of each boss 18 is provided with a locking lug receiving recess 25. The end ring 2 is formed by placing the segments 14 within the shell in abutting ring forming relation with the bosses 19 extending within the openings 8 in the shell 6 and with the bosses 18 engaging the inner surface of the shell 6 with the openings 21 alined with the openings 9 therein. The rings are retained in this position while assembling the shell ring 3 thereon by inserting short bolts 26 through alternate alined openings 9 and 21 as is best indicated by Figs. 1, 2 and 6.

The shell ring 3 is also formed by a plurality of abutting ring forming segments 27, 28 and 29 as is best seen in Fig. 7. The segments 27 each have a plane surfaced edge 31 and an oppositely facing stepped edge 32 presenting a plane surfaced riser portion 33 and a tread portion 34 adapted to abut the plane surfaced edge and the underside surface, respectively, of the next adjacent blade segment. The segment 28 has oppositely facing stepped edges 36 and 37 which are similar to the stepped edges 32 on the segments 27. The segment 29 is provided with oppositely facing plane surfaced edges 38 and 39. The inner surface of each of the segments 27, 28 and 29 is provided with locking or holding lugs 41 adapted to extend within the recess 25 provided in the bosses 18 on the coacting end ring segment 14 thereby retaining the shell ring segments 27, 28 and 29 against axial movement relative to the end ring segments 14. The shell ring segments 27, 28 and 29 are each provided with axially spaced openings 42 and 43 arranged for alinement with the series of openings 8 and 9, respectively, in the shell, and with the openings 42 also alined with the openings 12 in the rubbing ring 1. The shell ring segments 28 and 27 are assembled in abutting relation in the order named and in the manner indicated in Fig. 7, the segments being held in place by means of the locking lugs 41 and by means of bolts 44 and 46 which extend through the groups of alined openings 22, 8, 12 and 42 and through alternate groups of alined openings 21, 9 and 43, respectively, until completion of the ring can be effected by inserting the segment 29. The segment 29 is also secured in place by means of bolts 44 and 46 of which bolts 44 are shown in Fig. 7. The last or closing segment 29 is moved into place and its plane edges 38 and 39 coat with the stepped edges 37 and 32 on the abutting segments 28 and 27, respectively, and forms therewith a sealed

joint. The end portions of the segments 27 and 28 which engage the rubbing ring, present plane surfaced abutting edges as is best indicated in Figs. 1 and 2 which show that the stepped edges thereon terminate adjacent the proximate edge of the rubbing ring.

The shell 6 is also provided with another circumferentially extending series of openings 47 which connect the space 48 formed between the inner surface of the shell ring 3 and the outer opposed surfaces of the kiln shell 6 and the end ring 2 with the space 49 provided between the inner surface of the shell 6 and the opposed outer surface of the end ring 2 as is shown in Figs. 1, 2, 6 and 7. This construction provides in effect an outer annular cooling space 48 which communicates with an inner annular cooling space 49 through the openings 47 and through the space provided between the bosses 18. The inner surface of the shell 6 is provided with a suitable refractory lining 51 and the entire inner surface of the end ring 2 is also covered with a refractory lining 52 which forms a continuation of the shell lining 51. The rubbing ring 1 coacts with an annular seal ring 53 which in turn is associated with the hood structure 54 only a portion of which is shown in the interest of simplicity.

This construction provides a cooled end section construction since cooling air enters the space 48 through the axially extending passages 5 formed by the ribs 4 on the rubbing ring 1 and some of the air also passes from the space 48 through the openings 47 and into the space 49. The air leaves the space 49 by the passages provided between the bosses 18. The discharge end of the kiln is relatively hot and consequently a continuous gravity circulation of air takes place in the annular spaces 48 and 49 as indicated by the arrows shown on Figs. 1 and 2, thereby maintaining the temperature of the end and shell rings within safe limits. The bosses 19 extend snugly within the openings 8 thereby acting to maintain the end ring segments properly positioned within the shell ring 6 and consequently materially reduces the shearing stresses imparted to the retaining bolts 26, 44 and 46 by the relative expansion of the lining 51 and the shell 6. Moreover, the shell ring segments 27, 28 and 29 are interlocked with the outer end portion of the end ring segments 14 thereby preventing a material degree of looseness which is frequently experienced in the known structures of this type due to warpage of the coacting segments. Furthermore, the cooling of the end and shell ring segments prevents the occurrence of material differences in temperature and thereby the destructive relative expansion of the coacting parts which is also common in the known kiln end section constructions. In addition, the formation of the shell ring in the manner previously described provides a sealed ring structure which can be readily assembled and which can be readily disassembled in the event repairs are necessary.

The invention is of general application with respect to the end section construction for kilns employed in sintering or agglomerating nodular and finely divided materials of all types, and it should therefore be understood that it is not desired to limit the invention to the exact details of construction herein shown and described as various modifications within the scope of the appended claims may occur to persons skilled in the art.

It is claimed and desired to secure by Letters Patent:

1. A member adapted to coat and form with similar members a lining retaining end ring presenting a cylindrical portion adapted to engage the inner surface of a cylindrical kiln shell adjacent one end thereof and a converging portion which extends from said cylindrical portion in the direction of the said one end of the shell and in diverging relation with respect to the inner surface thereof comprising a metal ring segment having adjoining cylinder and cone frustum forming portions, and said segment having the outer surface of its cone frustum forming portion provided with a boss adapted to engage the inner surface of said shell.

2. A member adapted to coat and form with similar members a lining retaining end ring presenting a cylindrical portion adapted to engage the inner surface of a cylindrical kiln shell adjacent one end thereof and a converging portion which extends from said cylindrical portion in the direction of the said one end of the shell and in diverging relation with respect to the inner surface thereof comprising a metal ring segment having adjoining cylinder and cone frustum forming portions, and said segment having its outer surface provided with axially spaced bosses one of which is disposed on said cylinder forming portion and the other of which is disposed on said cone frustum forming portion.

3. A member adapted to coat and form with similar members a lining retaining end ring presenting a cylindrical portion adapted to engage the inner surface of a cylindrical kiln shell adjacent one end thereof and a converging portion which extends from said cylindrical portion in the direction of the said one end of the shell and in diverging relation with respect to the inner surface thereof comprising a metal ring segment having adjoining cylinder and cone frustum forming portions, said segment having its outer surface provided with axially spaced bosses one of which is disposed on said cylinder forming portion and the other of which is disposed on said cone frustum forming portion, said bosses each having an opening extending therethrough in a radial direction, and said segment having its inner surface provided with axially spaced bolt head receiving recesses disposed in alignment with and forming continuations of the openings in said bosses.

4. A kiln end section construction comprising a cylindrical shell, an end ring presenting a cylindrical portion adapted to engage the inner surface of said shell adjacent one end thereof and a converging portion, said converging portion having on its outer surface a circumferentially extending series of bosses adapted to engage the inner surface of said shell, said end ring being disposed in concentric relation with respect to said one end of the shell with said cylindrical portion engaging the inner surface of said shell adjacent the said one end thereof and with said bosses engaging the inner surface of said shell at points between said cylindrical portion and the said one end of the shell, means including said bosses for securing said end ring to the said one end of the shell, and a heat resistant lining covering the inner surface of said end ring.

5. A kiln end section construction comprising a cylindrical shell provided with a circumferentially extending series of openings adjacent one thereof, an end ring presenting a cylindrical portion adapted to engage the inner surface of said shell

adjacent said one end thereof and a converging portion, said converging portion having on its outer surface a circumferentially extending series of bosses adapted to engage the inner surface of said shell, said end ring being disposed in concentric relation with respect to said one end of the shell with said cylindrical portion engaging the inner surface of said shell adjacent the said one end thereof and with said bosses engaging the inner surface of said shell at points between said cylindrical portion and the said one end of the shell, said series of openings providing cooling fluid passages connecting the space surrounding said shell with the space provided between said converging portion of the end ring and the opposed inner surface of said shell, means including said bosses for securing said end ring to the said one end of the shell, and a heat resistant lining covering the inner surface of said end ring.

6. A kiln end section construction comprising a shell provided with a circumferentially extending series of openings adjacent one end thereof, a segmental end ring adapted to be inserted into said one end of the shell and having its outer surface provided with a plurality of axially spaced bosses some of which are arranged for alignment with the series of openings in said shell, said end ring being disposed in concentric relation with respect to the said one end of the shell with said some of the bosses extending within said openings in said shell and with the others of said bosses engaging the inner surface of said shell at points between said series of openings and the said one end of the shell, means including said bosses for securing said end ring to the said one end of the shell, and a heat resistant lining covering the inner surface of said end ring.

7. A kiln end section construction comprising a shell provided with axially spaced and circumferentially extending series of openings adjacent one end thereof, a segmental end ring having its outer surface provided with a plurality of bosses similarly arranged with respect to the openings in said shell, said bosses each having an opening extending therethrough in a radial direction, said end ring being disposed in concentric relation with respect to the said one end of the shell with some of said bosses extending within the openings of one of said series and with others of said bosses engaging the inner surface of said shell with their openings disposed in alignment with the openings in another of said series, means including said openings and bosses for securing said end ring to the said one end of the shell, and a heat resistant lining covering the inner surface of said end ring.

8. A kiln end section construction comprising a shell provided with a circumferentially extending series of openings adjacent one end thereof, a segmental end ring having its outer surface provided with a plurality of axially spaced bosses some of which are arranged for alignment with the series of openings in said shell, said end ring being disposed in concentric relation with respect to the said one end of the shell with said some of the bosses extending within the openings of said series and with the others of said bosses engaging the inner surface of said shell at points between said series of openings and the said one end of the shell, said others of said bosses being effective to maintain a major portion of the outer surface of said end ring spaced from the opposed inner surface of said shell so as to form therebetween an annular cooling space, means including said bosses for securing said end ring to the said one

end of the shell, and a heat resistant lining covering the inner surface of said end ring.

9. A kiln end section construction comprising a shell provided with two axially spaced and circumferentially extending series of openings adjacent one end thereof, a segmental end ring having its outer surface provided with a plurality of bosses similarly arranged with respect to the openings in said shell, said bosses each having an opening extending therethrough in a radial direction, said end ring being disposed in concentric relation with respect to the said one end of the shell with some of said bosses extending within the openings of the one of said series farthest from said one end of the shell and with others of said bosses engaging the inner surface of said shell with their openings disposed in alinement with the openings of the other of said series, said others of said bosses being effective to maintain a major portion of the outer surface of said end ring spaced from the opposed inner surface of said shell so as to form therebetween an annular cooling space, means including said bosses and openings for securing said end ring to the said one end of the shell, and a heat resistant lining covering the inner surface of said end ring.

10. A kiln end section construction comprising a shell, a rubbing ring secured in spaced concentric relation about an end portion of said shell, an end ring disposed partially within said end of the shell and having its entire inner surface provided with a heat resistant lining, a shell ring having one side portion engaging the edge portion of the exposed outer surface of said end ring and having its other side portion engaging the adjacent end of said rubbing ring, said rubbing and shell rings coacting with said shell and the exposed outer surface of said end ring to form therewith an annular cooling fluid space, and means securing said end ring to the said end of said shell and said shell ring to said end and rubbing rings.

11. A kiln end section construction comprising a shell, a rubbing ring secured in spaced concentric relation about an end portion of said shell, an end ring disposed partially within said end of the shell and having its entire inner surface provided with a heat resistant lining, a shell ring having one side portion engaging the edge portion of the exposed outer surface of said end ring and having its other side portion engaging the adjacent end of said rubbing ring, said shell ring having an interlocking connection with said end ring, said rubbing and shell rings coacting with said shell and the exposed outer surface of said end ring to form therewith an annular cooling fluid space, and means securing said end ring to the said end of said shell and said shell ring to said end and rubbing rings.

12. A kiln end section construction comprising a shell, provided with a circumferentially extending series of openings adjacent one end thereof, a rubbing ring secured in spaced concentric relation about an end portion of said shell, an end ring disposed partially within said end of the shell and having its entire inner surface provided with a heat resistant lining, a shell ring having one side portion engaging the edge portion of the exposed outer surface of said end ring and having its other side portion engaging the adjacent end of said rubbing ring, said rubbing and shell rings coacting with said shell and the exposed outer surface of said end ring to form therewith an annular cooling fluid space, said series of openings providing cooling fluid passages connecting the space provided between said

shell and rubbing ring with the space provided between said covering portion of the end ring and the opposed inner surface of said shell, and means securing said end ring to the said end of said shell and said shell ring to said rubbing ring.

13. A kiln end section construction comprising a shell provided with a circumferentially extending series of openings adjacent one end thereof, a rubbing ring disposed in spaced concentric relation about said one end of said shell, a segmental end ring having its outer surface provided with a plurality of spaced bosses arranged for alinement with the openings in said shell, said end ring being disposed partially within said one end of the shell with said bosses extending within said openings, a shell ring having one side portion engaging the edge portion of the exposed outer surface of said end ring and having its other side portion engaging the adjacent end of said rubbing ring, said rubbing and shell rings coacting with said shell and the exposed outer surface of said end ring to form therewith an annular cooling fluid passage, means including said bosses for securing said end ring to the said one end of the shell and said shell ring to said end and rubbing rings, and a heat resistant lining covering the inner surface of said end ring.

14. A kiln end section construction comprising a shell provided with a circumferentially extending series of openings adjacent one end thereof, a rubbing ring secured in spaced concentric relation about said one end of the shell, a segmental end ring having its outer surface provided with a plurality of axially spaced bosses some of which are arranged for alinement with the series of openings in said shell, said end ring being disposed partially within said one end of the shell and with some of the bosses extending within said openings and with the others of said bosses engaging the inner surface of said shell at points between said series of openings and the said one end of the shell, said others of said bosses being effective to maintain a major portion of the outer surface of said end ring spaced from the opposed inner surface of said shell, a shell ring having one side portion engaging the edge portion of the exposed outer surface of said end ring and having its other side portion engaging the adjacent end of said rubbing ring, said rubbing and shell rings coacting with said shell and the exposed outer surface of said end ring to form therewith an annular cooling fluid passage forming a continuation of the space provided between the outer surface of said end ring and the opposed inner surface of said shell, means including said bosses for securing said end ring to the said one end of said shell and said shell ring to said end and rubbing rings, and a heat resistant lining covering the inner surface of said end ring.

15. A kiln end section construction comprising a shell provided with two axially spaced and circumferentially extending series of openings adjacent one end thereof, a rubbing ring secured in spaced concentric relation about said one end of the kiln and having a series of openings therein disposed in alinement with the openings of the circumferentially extending series farthest from the said one end thereof, a segmental end ring having its outer surface provided with a plurality of bosses similarly arranged with respect to the openings in said shell, said bosses each having an opening extending therethrough in a

radial direction, said end ring being disposed partially within the said one end of the shell with some of said bosses extending within the openings of said series farthest from the said one end of the shell with others of said bosses engaging the inner surface of said shell with their openings disposed in alinement with the openings in the other of said circumferentially extending series, said others of said bosses being effective to maintain a major portion of the outer surface of said end ring spaced from the opposed inner surface of said shell, a shell ring having one side portion engaging the edge portion of the exposed outer surface of said end ring and having its other side portion telescopically engaging the adjacent end of said rubbing ring, said rubbing and shell rings coacting with said shell and the exposed outer surface of said end ring to form therewith an annular cooling fluid space forming a continuation of the space provided between the outer surface of said end ring and the opposed inner surface of said shell, said shell ring having a series of openings therein disposed in alinement with the openings in said other of the circumferentially extending series, 25 means including said bosses and openings for

securing said end ring to the said one end of said shell and said shell ring to said end and rubbing rings, and a heat resistant lining covering the inner surface of said end ring.

- 5 16. In a kiln, a shell ring construction formed by a plurality of abutting ring forming segments and including at least one segment having a plane surfaced edge and an oppositely facing stepped edge presenting a plane surfaced riser 10 portion and a tread portion adapted to abut the plane surfaced edge and the underside surface, respectively, of the next adjacent segment, another segment having oppositely facing stepped edges similar to the stepped edge on said one segment with one of its said stepped edges abutting the plane surfaced edge on the said one segment and with its other stepped edge disposed in spaced opposed relation with respect to the stepped edge on the said one or a similar segment, and a ring closing segment having oppositely facing plane surfaced edges disposed in abutting relation with respect to the spaced opposed stepped edges presented by said another segment and the said one or a similar segment. 15 20
